Jeffrey E. Pechinger

UNITED STATES PATENT OFFICE

161,522

CHOCOLATE LAMB

Richard M. Palmer, Reading, Pa.

Application August 9, 1950, Serial No. 11,678

Term of patent 14 years

(Cl. D82—2)

To all whom it may concern:

Be it known that I, Richard M. Palmer, a citizen of the United States of America, residing at 800 Old Wyomissing Road, Reading, in the county of Berks and State of Pennsylvania, have invented a new, original, and ornamental Design for a Chocolate Lamb, of which the following is a specification, reference being had to the accompanying drawings, forming part thereof.

Fig. 2 is a rear elevational view thereof.

Fig. 3 is a side elevational view showing the other side of the chocolate lamb and

Fig. 4 is a front elevational view thereof.

I claim:

The ornamental design for a chocolate lamb, as shown.

RICHARD M. PALMER.
